DESIGN FOR A TOOL SETTING AND CHECKING GAUGE

Harold L. Bartelt, Beloit, Wis.

Application March 27, 1942, Serial No. 106,343

Term of patent 14 years

To all whom it may concern:

Be it known that I, Harold L. Bartelt, a citizen of the United States, residing at Beloit, in the county of Rock and State of Wisconsin, have invented a new, original, and ornamental Design for a Tool Setting and Checking Gauge, of which the following is a specification, reference being had to the accompanying drawing, forming a part thereof.

Figure 1 is a rear end view of a tool setting and checking gauge, showing my new design.

Figure 2 is a side view of the design shown in Figure 1.

Figure 3 is a top plan view of the design shown in Figures 1 and 2.

I claim:

The ornamental design for a tool setting and checking gauge, as shown.

HAROLD L. BARTELT.
